UNITED STATES PATENT OFFICE

ALFRED G. RANNEY, OF SAN ANTONIO, TEXAS

GOLF GAME

Application filed June 17, 1930. Serial No. 461,772.

This invention relates to certain new and useful improvements in game apparatus, and the primary object of the invention is to provide an improved game simulating a game of golf.

A still further object of the invention is to provide a golf simulating game which may be played indoors on a table or any other like and suitable support, which will require a certain amount of skill on the participants of the game, while at the same time, to provide a game of the character above mentioned which is comparatively simple in its manner of construction and method of play, and which may be enjoyed, and prove of interest to both young and old alike.

Broadly, the invention consists in the provision of a golf simulating game embodying a box or receptacle having a relatively flat face provided with a plurality of depressions connected through the medium of tunnels, and each of the depressions being provided with an inclined bottom whereby the depression is relatively deep at one end thereof, and relatively shallow at the opposite end thereof, the relatively shallow ends of the depressions or recesses communicating with the relatively deep ends of adjacent recesses through the medium of the aforementioned tunnels, together with a ball or other suitable game piece to be moved over the bottom of the box by tilting the latter, the object of the game being the passage of the ball or game piece from one recess to the other in a predetermined successive order, and within a minimum amount of time.

Other objects and advantages of the invention will become apparent during a study of the following description, taken in connection with the accompanying drawings wherein:

Figure 1 is a plan view of my improved game.

Fig. 2 is a longitudinal vertical sectional

view therethrough, taken substantially on the line 2-2 of Fig. 1.

Fig. 3 is a fragmentary detail sectional view, taken substantially on the line 3-3 of Fig. 1.

Fig. 4 is a detail sectional view taken substantially on the line 4-4 of Fig. 1.

Fig. 5 is a detail sectional view taken substantially on the line 5-5 of Fig. 1.

Fig. 6 is a detail sectional view taken substantially on the line 6-6 of Fig. 1.

With reference more in detail to the drawings, it will be seen that my improved game comprehends the provision of a box-like structure including a bottom or base 10 formed of any suitable material and preferably of elongated rectangular configuration.

Secured to the sides and end edges of the base and forming the side and end walls for the box is a strip of metal or any other suitable material 11 which at its upper edge extends above the top surface of the base 5 and at said upper edge is provided with an in-turned flange 12 for retaining in place, a suitable transparent cover plate 13.

The edges of the cover plate 13 are retained within the confines of the wall formed by the strip 11 between the flange 12 and a suitable spacing strip 14 of felt or like material resting between the cover 13 and base 10.

Provided in the base 10 are a plurality of recesses. There may be any desired number of such recesses, however, for the sake of example, I have shown nine of the same, each constituting the "tee" fairway and so "green" embodied in the layout of a golf course, the recesses being consecutively numbered 1, 2, 3, 4, 5, 6, 7, 8 and 9.

Broadly, each of the recesses at one end is relatively deep and at said deep end the bottom of the recess is relatively flat to constitute a "tee" 15, from the "tee" 15 the bottom of the recess gradually slopes upwardly and forwardly to provide an inclined "fairway" 16, leading to a relatively flat bottom consti-

tuting a "green" 17, at the forward and relatively shallow end of the recess.

At said relatively shallow end or "greens", each recess is provided with a vertical hole 18 simulating the "cup". Leading from the hole or "cup" 18, through the base 10 is a tunnel or passage 19, to terminate at the deepest end of the next adjacent recess for connecting the cup 18 of each recess with the "tee" 15 of the next adjacent succeeding recess.

Thus it will be seen that in its broadest aspect, the invention comprehends a game embodying a plurality of recesses successively connected by tunnels whereby a moving object may pass successively from one recess to another through the tunnels communicating the recesses, together with the idea of gaining elevation by upslopes enabling the moving object or game piece, which game piece is preferably in the nature of a ball, to be "holed out" at the end of the recess, indicating, as it were, the completion of one "hole" during a "round" of golf.

The recesses are all of any desired outline or shape, and of any length, it being intended, that the recesses be of varied shapes and lengths, no two of the recesses being identical.

In order to present obstacles to the moving ball, and to render somewhat difficult the placing of the ball in the holes in successive order, thus enhancing a game of this character, there is provided for each recess such obstacles, as for example, "traps", "hazards", and the like, simulating such obstacles as are found in and constitute a part of a "golf course."

The arrangement of such "traps", "hazards", etc., may be as desired. For example, recess 1 is practically free of such obstacles, presenting little or no difficulty to the participant for "holing out", or in other words, the depositing of the ball in the hole of recess 1. The same is true of recess 2. However, as is apparent, each successive recess becomes more difficult.

In this connection, it will be seen that recess 3 is somewhat in the nature of a distorted U, and at one side of its "fairway" 16 is provided with an elongated depression 20 at the bight portion of the U, and on the other side adjacent said bight with a relatively short depression 21, said depressions 20, 21 forming "traps".

The recess 3 may be further provided just forwardly of the "greens" 17, with a transverse depression or ditch 22.

Recess 4, intermediate the ends thereof, is divided by a wall 23 having an open-ended tube 24 extending therethrough at an incline corresponding to the slope of the "fairway" 16 providing a restricted passage leading from the "tee" 15 to "greens" 17.

Obviously, wall 23 provides a stop for the rolling ball to prevent rolling of the ball

onto the "greens" prior to passing thru tube 24. Projecting inwardly from the wall of recess 4 is an extension 25, the free end of which is, in alignment with tube 24 to one side of hole 18, and against which the ball is liable to strike when emerging from the tube, thus providing a "hazard" for deflecting the ball from its true course to the hole.

Recess 5, is more or less L-shaped, and at the junction of the arms of the L provided with a projection or "hazard" 26 restricting the width of the recess at this point. The side of the "fairway" opposite the "hazard" 18 inclines somewhat as clearly suggested in Fig. 5 so that obviously the ball striking against the "hazard" 26 is liable to roll up the inclined wall of the recess onto the top surface of the base, thus requiring further manipulation of the box or base for returning the ball to the recess 5, prior to the ball entering the next adjacent recess 6, which must be accomplished according to the rules of the game, since according to the rules of the game, it is necessary that the course be completed only by the ball passing successively from one recess to another in accord with the numbering of the recesses, that is, the ball must pass first from recess 1 into recess 2, and then into recess 3 and so on in order until the ball has been returned to the starting or recess 1.

On diametrically opposite sides of the "hole" 18 of recess 5, there is further provided relatively deep cavities 27 into which the ball may lodge, requiring further manipulation of the base 10 to dislodge the ball in an attempt to roll the ball into hole 18 in order to proceed to the next recess 6.

Recess 6 may on opposite sides of its fairway be provided with depressions 27, that are longitudinally curved, it being noted that recess 6 is substantially an L. At the forward ends of the depressions, or traps 27, are a pair of inwardly directed extensions 28 terminating in spaced relation at their inner ends to provide therebetween a narrow passage from the "fairway" to the "green". A relatively small depression or trap 29 may be formed in the "fairway" in advance of the projection hazards 28.

The recess 7 as shown is somewhat elongated, being narrow at one end and gradually increasing in width toward the forward end. Adjacent the upper or raised portion of its bottom, there may be provided a concave depression or trap 30, between which and the hole 18 is formed a transverse depression or ditch 31.

In its arrangement of hazards etc., recess 8 is somewhat akin to recess 6, in that it also includes depressions or traps 32 on opposite sides of the fairway together with obstruction hazards 33 similar to hazards 28 of recess 6.

In recess 8, the narrow passage formed be-

tween the projections 33—33, leads to a jump gap 34. As to recess 9, it will be noted that the same is substantially elongated, and at opposite sides thereof, the fairway of the recess may be lined with any type of obstruction 35, such as may simulate trees, etc., narrowing the fairway leading to the "putting green".

Obviously, the recesses need not be restricted to their specific characteristics as herein shown and described somewhat in detail, but it is apparent that the recesses may be of any desired width, length, shape, and that the traps, hazards, etc., be rearranged as may be desired, to require utmost skill to direct the ball from one recess to the other, in the proper order and in a minimum amount of time.

To facilitate tipping the box or base to cause the rolling of the ball in such a manner as to complete "the round", there is provided on the bottom of the base, at the center thereof, a ball-like member 36 for rockably supporting the base or box on a table or like support. Or in simpler form, for it is contemplated that the game apparatus may be made small in size and shape and of light material, the ball-like member 36 may be omitted and playing may be consumed by holding and tipping it while held in both hands.

The rules for playing the game are simple. The game may be played by one or more persons. The object of the game is to complete "a round" in a minimum amount of time, it being necessary that the ball pass from one recess to another in proper sequence. Each player is timed from his start at No. 1 hole, that is the hole of recess 1, and until he "holes out" at No. 9 "green" or the hole of recess 9. The player who requires the least time (minutes and seconds) to make a "round" wins.

From the foregoing then, it will be seen that I have devised a novel form of game simulating to a marked degree the game of golf, and at the time, while requiring a certain amount of skill is easy to understand and practice, and that this game affords amusement both to young and old alike.

It is thought that from the foregoing description, taken in connection with the accompanying drawings, a clear understanding of the operation, construction, and the manner of operation of a game of this character will be had by those skilled in the art, without a more detailed description.

Even though I have herein shown and described the preferred embodiment of my invention, it is to be understood that the same is susceptible to changes fully comprehended by the spirit of the invention as herein described, and the scope of the appended claims.

Having thus described my invention, what I claim as new is:

1. In a game of the class described, an elongated rectangular base having one or more depressions formed therein, each depression being relatively deep at one end and relatively shallow at its opposite end, the bottom of the depression at said ends being relatively flat and having an intermediate portion sloping from the flat bottom portion of the deep end upwardly to the flattened portion of the shallow end, tunnels formed in the base connecting said depression, said tunnels leading from the shallow end of the depressions to the deep end of the next adjacent depression, and a ball movable over the base.

2. In a game of the class described, a base having a plurality of depressions formed therein, each depression being relatively deep at one end and relatively shallow at its opposite end, and at its shallow end provided with a vertical hole, passages formed in the base connecting said depressions, said passages leading from the lower ends of the holes of the depressions to the deep ends of adjacent depressions whereby a ball may pass from one depression to the next adjacent depression through a hole and passage communicating therewith, and a ball movable over the base.

3. In a game of the class described, a box including a bottom, walls rising from the bottom, and a transparent cover plate arranged within the confines of the walls in spaced relation to the bottom to provide a closure for the box, said bottom provided with a plurality of recesses, each of said recesses having its bottom relatively flat at the ends of the recesses, an intermediate portion of the bottom sloping from the flattened portion of the bottom at one end of the recess to the flattened portion of the bottom at the opposite end of the recess, the flattened portion of the bottom of the recess at the deepest end of the recess constituting a "tee", the flattened portion of the bottom of the shallow end of the recess constituting a "green", and the inclined portion of the bottom of the recess constituting a fairway leading from the tee to the green, a ball movable over the bottom within said box, each of said recesses at the shallow end provided with a vertical hole constituting a "cup" for accommodating the ball, passages connecting said recesses, there being one passage leading from the hole of one of said recesses to the relatively deep end of a next adjacent recess, whereby to provide a passage for conducting the ball from the hole of one recess to the tee of a next adjacent recess.

4. In a game of the class described, a box including a bottom, walls rising from the bottom, a transparent cover plate arranged within the confines of the walls in spaced relation to the bottom to provide a closure for the box, said bottom provided with a plurality of recesses, each of said recesses having its bottom relatively flat at the ends of the

recesses, an intermediate portion of the bottom sloping from the flattened portion of the bottom at one end of the recess to the flattened portion of the bottom at the opposite end of the recess, the flattened portion of the bottom of the recess at the deepest end of the recess constituting a "tee", the flattened portion of the bottom of the shallow end of the recess constituting a "green", and the inclined portion of the bottom of the recess constituting a fairway leading from the tee to the green, a ball movable over the bottom within said box, each of said recesses at the shallow end provided with a vertical hole constituting a "cup" for accommodating the ball, passages connecting said recesses, there being one passage leading from the hole of one of said recesses to the relatively deep end of a next adjacent recess, whereby to provide a passage for conducting the ball from the hole of one recess to the tee of a next adjacent recess.

5. In a game of the class described, a box including a bottom, walls rising from the bottom, a transparent cover plate arranged within the confines of the walls in spaced relation to the bottom to provide a closure for the box, said bottom provided with a plurality of recesses, each of said recesses having its bottom relatively flat at the ends of the

5 recesses, an intermediate portion of the bottom sloping from the flattened portion of the bottom of the recess to the flattened portion of the bottom at the opposite end of the recess, the flattened portion of the bottom of the recess at the deepest end of the recess constituting a "tee," the flattened portion of the bottom of the shallow end of the recess constituting a "green," and the inclined portion of the bottom of the recess constituting a fairway leading from the tee to the green, a ball movable over the bottom within said box, each of said recesses at the shallow end provided with a vertical hole constituting a "cup" for accommodating the ball, passages connecting said recesses, there being one passage leading from the hole of one of said recesses to the relatively deep end of a next adjacent recess, whereby to provide a 10 passage for conducting the ball from the hole of one recess to the tee of a next adjacent recess, and a member secured to the bottom of said box exteriorly of the box to provide a support for rockably supporting the 15 box on a table or the like.

20 5. In a golf game of the class described, a base having a plurality of recesses formed therein, tunnels connecting said recesses, said tunnels leading from the end of one recess 25 to the adjacent end of the next adjacent recess whereby said recesses and tunnels provide a tortuous ball conducting passage, and a ball movable on the base and adapted by manipulation of the base to pass from one recess to the other through said passages.

30 6. In a golf game of the class described, a base having a plurality of recesses formed therein, tunnels connecting said recesses, said tunnels leading from the end of one recess 35 to the adjacent end of the next adjacent recess whereby said recesses and tunnels provide a tortuous ball conducting passage, a ball movable on the base and adapted by manipulation of the base to pass from one recess to the other through said passages, said recesses respectively having the bottom thereof sloping upwardly from a point inwardly from one end of the recess to a point inwardly from the opposite end of the 40 recess.

45 7. A game apparatus comprising in combination a box, a transparent cover for the box, said box having the bottom thereof provided with a plurality of recesses, each of 50 which constitutes a complete "hole" in a game of golf and embodies a tee, a "putting" green and a fairway connecting the tee with the "putting" green and tunnels connecting the "putting" greens of the recesses with the tees of adjacent recesses to thereby permit passage of a playing element at the completion of one hole to the tee of an adjacent recess for subsequently completing the hole 55 60 defined by the last referred to recess, and a

ball adapted to travel over the bottom of the box upon tilting of the box.

65 8. A game apparatus comprising in combination a box, a transparent cover therefor, said box provided with a plurality of recesses 70 in the bottom thereof, tunnels connecting the recesses, a ball movable over the bottom of the box to pass from one recess to another through a tunnel connecting the recesses, and means arranged in each recess in the 75 path of movement of the ball for impeding the progress of the ball.

80 In testimony whereof I affix my signature.
ALFRED G. RANNEY.
